Filed Aug. 4, 1959, Ser. No. 57,064

Term of patent 14 years

(Cl. D87—3)

The figure is a plan view of a plastic coated fabric showing my new design.

A single unit of the design is substantially comprised within the area defined by the indicating lines shown on the drawing, which unit is repeated over the surface of the fabric in the relation indicated.

I claim:

The ornamental design for a plastic coated fabric or similar article, as shown and described.
